[57] CLAIM

The ornamental design for a roller skate, as shown and described.

DESCRIPTION

FIG. 1 is a side elevational view of one side of a roller skate illustrating our new design, the other side appearing substantially a mirror image of the side shown;
FIG. 2 is a top plan view thereof;
FIG. 3 is a rear elevational view thereof; and
FIG. 4 is a front elevational view thereof.

*Fig. 1.**Fig. 2.**Fig. 3.**Fig. 4.*
